UNITED STATES PATENT OFFICE.

FRANCIS C. MASON AND JOHN W. SHANAHAN, OF GRAND RAPIDS, MICHIGAN, ASSIGNORS TO BISSELL CARPET SWEEPER COMPANY, OF GRAND RAPIDS, MICHIGAN, A CORPORATION OF MICHIGAN.

BALL-BEARING.

No. 891,943.

Specification of Letters Patent.

Patented June 30, 1908.

Application filed August 20, 1907. Serial No. 389,390.

To all whom it may concern:

Be it known that we, FRANCIS C. MASON and JOHN W. SHANAHAN, both citizens of the United States of America, residing at 5 Grand Rapids, in the county of Kent and State of Michigan, have invented certain new and useful Improvements in Ball-Bearings; and we do hereby declare the following to be a full, clear, and exact description of the invention, such as will enable others skilled in the art to which it appertains to make and use the same.

Our invention relates to improvements in ball bearings, and more particularly to ball 15 bearings for carpet sweepers, and its object is to provide a suitable compact and easily manufactured ball bearing, adapted to operate in connection with the supporting wheels of a carpet sweeper and the spring supports for 20 the same, and it consists essentially of an annular case having a radial arm and comprising two stamped sheet metal members attached to each other, a ball race surrounding the central opening, balls in the race and a 25 collar externally grooved to receive the balls, and having an axial opening to receive the hub of the wheel, all as will more fully appear by reference to the accompanying drawings, in which:

30 Figure 1. is an end elevation of a carpet sweeper having our improved ball bearings attached; Fig. 2. a plan view of the same with a portion of one wheel broken away; Fig. 3. an enlarged vertical section of one of 35 the wheels and the bearing for the same; and Figs. 4 and 5, details of the respective stamped sheet metal members before assembling.

Like numbers refer to like parts in all of the figures.

40 1 represents the case of a carpet sweeper; 2 the guard bar of the same supporting the brush shaft 3. 4 supporting wheels carrying the carpet sweeper and engaging the brush shaft to rotate the same. These wheels are 45 supported in parallel planes by connecting rods 10 inserted in the axis of the hubs of the respective wheels, and connecting the same in pairs. These rods extend through enlarged openings (not shown) in the ends of the 50 sweeper case in which openings they are laterally movable and do not support the said case, which latter is supported on the spring supports 11 attached to the case by being inserted in slots in the bail guards 14 and secured therein by clips 12.

5 represents the hubs of the wheels, each of which is made externally concentric with the axis of the wheel, and inserted in a sleeve 6 surrounding the hub and rotative therewith, this sleeve having an external groove 60 traversed by balls 9 inclosed in the ball races of the case formed at 8 and 13 in the respective opposing portions of the case, said case having an axial opening to receive the sleeve 6, which opening is surrounded by said ball 65 race.

The case is substantially annular in shape and provided with a radially extended arm 7 perforated to pivotally receive the end of the spring support 11.

70 One of said sheet metal members is preferably extended beyond the other all around its margin as at 15 in Fig. 4, and folded over the same to secure the two members to each other, as at 15 in Fig. 3. Thus when these 75 case members are assembled with the balls 9 and sleeve 6 inserted therein, the balls and sleeve are retained therein and can in this condition be readily manipulated as an integral structure or placed in the finished machine as illustrated in Fig. 1. We are thus able to provide a compact and satisfactory 80 ball bearing adapted to be located within the cup-shaped wheel shown, and having an arm to pivotally connect the bearing to the spring 85 support 11 of the carpet sweeper.

What we claim is:

1. A ball bearing for carpet sweepers, comprising a wheel having a projecting hub, a sleeve detachably surrounding the hub and 90 having a circumferential groove, a case surrounding the sleeve and formed of two stamped sheet metal parts secured to each other and having radial arms adapted to be pivotally attached to the spring supports of a 95 carpet sweeper, each part having a ball race surrounding the sleeve, and balls in the said races and engaging the groove in the sleeve.

2. In a ball bearing for a carpet sweeper, a case comprising two stamped sheet metal 100 members each having an axial opening, and a ball race surrounding said opening, the edge of one member being folded over the edge of the other member; balls in the ball races, and a sleeve in said openings and having a circumferential groove engaged and traversed by the balls and an axial opening to receive the hub of a wheel, and means for attaching said case to a support.

3. In a ball bearing for a carpet sweeper, 110

the combination of a case comprising two annular sheet metal members each having an axial opening and a ball race surrounding said opening, each member also having a radial and perforated arm, said members being secured to each other by folding the edge of one over the edge of the other; balls in the ball race, and a sleeve in said openings having a circumferential groove engaged and

traversed by the balls and an axial opening 10 to receive the hub of a wheel.

In testimony whereof we affix our signatures in presence of two witnesses.

FRANCIS C. MASON.
JOHN W. SHANAHAN.
